UNITED STATES PATENT OFFICE

OTTO BAMBERGER, OF DUISBURG, GERMANY, ASSIGNOR TO DEUTSCHE MASCHINEN-FABRIK AKTIENGESELLSCHAFT, OF DUISBURG, GERMANY

MANUFACTURE OF SEAMLESS TUBES

Application filed March 25, 1926, Serial No. 97,328, and in Germany February 20, 1926.

This invention relates to a method for the manufacture of seamless tubes from hard material such as alloyed steels, special steels and the like.

5 Hitherto it has been necessary to manufacture such tubes by pressing and further treatment on draw benches owing to the hardness and sensitiveness of the material, as the perforation of the blank by means 10 of oblique rolling trains was rendered impossible owing to the hardness and nature of the material. The operation of drawing is therefore expensive and not economical, so that in consequence a high price 15 was required for seamless tubes made from such material.

According to the present invention tubes from such material can be manufactured in a manner that is simple and at a reduced 20 cost by the use of the pilgering process.

The novelty of the invention consists in first perforating the blank in a press to a thimble form, and then directly reducing it in diameter and thickness of wall on the 25 draw bench to such an extent that it can be further treated in an immediately succeeding operation by finishing the rolling by pilgering.

The plant for carrying out the new process 30 may be conveniently constructed so that the heated solid block coming from the furnace is first formed in the shape of a thimble in a press, and then, after the blank has passed through a heating furnace it is 35 reduced in dimensions in a draw press, and after having had its closed end removed by means of a saw placed immediately behind the draw press it is again heated and passed on to the pilgering mill for final treatment. 40 For this purpose it is advantageous to heat the blank in the heating furnace between the several pressing and rolling operations. In this way it is possible in contradistinction 45 to the methods hitherto employed for the manufacture of such tubes, economically to pilger the blank in the manufacture of tubes of specially hard material or of tubes with special properties.

50 In the accompanying drawing is diagram-

matically shown a constructional example of a plant according to the invention.

As illustrated in the accompanying drawing the press B serves to move the quadrilateral blocks which are brought up on a 55 narrow gauge rail wagon to the furnace A in which they are turned several times so as to ensure their being well and uniformly heated. Through the outlet door of the furnace A the blocks pass into a preliminary 60 thimble-forming press C, in which they undergo a preliminary shaping into a form resembling a thimble. From the press C the tubular blanks pass through a heating furnace D and thence into the draw 65 press E, where the diameter and the thickness of the wall of the blank are reduced by one or more draw rings. As the blank emerges from the draw press E, a saw F placed behind the draw press cuts off the 70 closed end. The tubular blank is then taken to another heating furnace G and passes out to the delivery or feeding apparatus H, which passes it on to the pilgering mill J.

In this latter the rolling of the tubes is completed, and they then pass by means of the delivery shoot L to the saw M which cuts off the ends. The train of rolls N conveys the tubes or blanks to the bed O where 80 they cool down.

I claim:

1. A method for the manufacture of seamless tubes of hard metals, such as alloyed steels and so-called special steels, consisting of the following steps in succession: the pressing of the heated blank of hard metal into the form of a thimble, reheating the thimble-like blank thus formed, drawing down the reheated blank and reducing the 90 blank in diameter as well as thickness of wall so as only partially to effect the reduction of diameter and thickness required to produce the finished tube; cutting off the closed end of the blank to produce a cylinder, again reheating the cylindrical blank and then reducing the reheated blank in diameter and thickness to final dimensions in a pilgering mill, substantially as hereinbefore described.

2. A plant for the manufacture of seam-
less tubes of hard metal such as alloyed
steels and special steels according to the
method of claim 1 consisting in combina-
tion of the following apparatus in succes-
sive adjacent relation: a furnace adapted
to heat the blanks of hard metal, a press
adapted to press the said blanks into a
thimble form, a reheating furnace adapted
10 to reheat the said pressed blanks, a draw
press adapted partially to reduce the said
pressed blanks in diameter and thickness of
wall, a saw adapted to remove the closed
end from the said blanks, a further reheat-
15 ing furnace adapted to further reheat the
said pressed, drawn and cut blanks and a
pilgering mill adapted to reduce to final
dimensions of diameter and thickness the
said pressed, reheated, drawn, and further
20 reheated blanks, substantially as herein-
before described.

OTTO BAMBERGER.
